UNITED STATES PATENT OFFICE.

JOHN H. THIELER, OF LENORA, KANSAS.

BOX.

No. 845,596.

Specification of Letters Patent.

Patented Feb. 26, 1907

Application filed August 2, 1906. Serial No. 328,958.

To all whom it may concern:

Be it known that I, JOHN H. THIELER, a citizen of the United States, residing at Lenora, in the county of Norton and State of Kansas, have invented certain new and useful Improvements in Boxes, of which the following is a specification:

My invention relates to boxes or cases adapted for shipping articles, such as eggs, and particularly to the type of boxes or cases that may be folded and collapsed for storage or transportation.

It has for its object to produce a box formed of corrugated sheet metal and having its sides, ends, cover, and bottom hinged together and adapted to be folded flat and provided with means for securely bracing the parts when unfolded and the box set up.

Referring to the drawings, Figure 1 is a perspective view of a box embodying my invention, parts thereof being broken away to show the interior construction. Fig. 2 is a rear view in elevation. Fig. 3 is a cross-sectional view. Fig. 4 is a view of the box folded.

In the drawings, A A' indicate the sides of the box, and B the ends, all formed of corrugated sheet metal. Around each of the side pieces A A' is bent a rod E, to which it is secured by flaps a or by turning over the edges of the sides, thus stiffening these parts. The upright portions b of the rods are adapted to form pintles or pivots along the corners of the box, by which the sides and ends are hinged to each other, so that the box may be collapsed or folded, as shown in Fig. 4. Along the upper edge of each side is a strip of wood covered with metal, as shown at b', for stiffening the end pieces. These strips or ribs form handles, so that the box may be easily handled.

C indicates the bottom of the box, also formed of corrugated sheet metal and having along one edge thereof (preferably the front) the flaps a', by which it is hinged to the rod e along the lower edge of the side piece A. Near the opposite edge of the bottom, and preferably secured to the inner face thereof, are the locking-plates D, the outer ends of which plates are bent upward at substantially right angles, as shown at d, and are arranged to lie behind the rod E and enter apertures or slots d', formed in the side A' near its lower edge, and through which they pass, so as to lie against the inner face of such side. In order to lock the bottom in place, I pro-

vide each plate D with a pivoted catch adapted to engage with the rod and lock the ends d in the slots d' and behind the rod E. When it is desired to fold the box flat, the catch is swung inward and out of engagement with the rod, and then the bottom can be disconnected from the side.

F indicates a partition hinged at f to the bottom, so that it may be folded flat thereupon. On the inner faces of the side pieces A A', I provide means, such as shown at f', for holding the partition in upright position when it is desired to divide the box into two compartments.

G indicates the cover, also formed of corrugated sheet metal and hinged to the rod E along the upper edge of the side A' by the flaps a. The cover G is held in closed position by means of a pair of spring-straps secured to the inner face of the side piece A and having their ends bent at substantially right angles, as shown at g, which ends extend through slots g' in the side A and are adapted to engage with and enter slots h in overlapping straps H, secured to the cover. When the cover is closed, the spring-straps are pressed in until they come opposite or register with the slots in the straps, when they can interlock therewith. To lock the box or prevent the spring-straps from being accidentally pressed in, holes are provided therein adapted to receive the hasp of a padlock, pin, or an equivalent.

By constructing my box as herein described it will be seen that all the parts are hinged together, and that it may be folded flat for storing or shipping purposes or opened or unfolded, and when in this condition the cover and bottom are firmly locked to the sides, whereby a light, strong, durable shipping-case is formed.

I do not wish to be understood as being limited to the particular construction shown in the drawings, as many changes in the style and form of case or box described herein may be made without departing from the spirit of my invention.

What I claim is—

1. In a foldable box, the combination of the side and end pieces, and rods extending around the side pieces to stiffen them, and arranged to form the pivots by which the side and end pieces are united, one of the side pieces having slots formed along its lower edge, a bottom hinged to one of the side pieces, and locking-plates arranged to extend

behind one of the rods and into the said slots in the side piece for holding the bottom in position.

2. In a foldable box, the combination of 5 side and end pieces, a pair of rods bent around the side pieces and secured thereto, a bottom hinged to one of the rods, a pair of locking-plates secured to the bottom arranged to extend behind the other rod, and catch-pieces also arranged to engage with the last-mentioned rod and lock the bottom in position.

3. In a collapsible box, the combination of 10 side and end pieces, a bottom hinged to the lower edge of one of the side pieces, the oppo- 15

site side piece being formed with a pair of slots, a rod extending along the lower edge of the last-mentioned side piece, a pair of locking-plates secured to the bottom, the outer ends of the plates being bent at substantially 20 right angles to the bottom, and arranged to lie behind the rod and extend through the said slots, and catch-pieces pivoted to the locking-plates arranged to engage with the rod and lock the bottom in place.

JOHN H. THIELER.
